UNITED STATES PATENT OFFICE.

THOMAS FERRY, OF CLEVELAND, OHIO.

PROCESS OF UPSETTING SET-SCREWS, CAP-SCREWS, AND THE LIKE.

1,069,659.

Specification of Letters Patent.

Patented Aug. 5, 1913.

Application filed April 11, 1908. Serial No. 426,428.

To all whom it may concern:

Be it known that I, THOMAS FERRY, a citizen of the United States of America, residing at Cleveland, in the county of Cuyahoga and State of Ohio, have invented certain new and useful Improvements in Processes of Upsetting Set-Screws, Cap-Screws, and the Like; and I hereby declare the following to be a full, clear, and exact description of the invention, such as will enable others skilled in the art to which it pertains to make and use the same.

This invention relates to a process for upsetting or heading blanks for cap-screws, set-screws and the like.

With the processes heretofore employed only a limited portion or length of the blank or stock can be upset to form the head, or, in other words, the size of the head for a certain diameter of material is limited, for the reason that if it is attempted to upset a greater length of material, the punch or upsetting die on striking the end of the blank will cause the latter to buckle or bend resulting in a very imperfect or unsymmetrical head being formed. Consequently, if a head of a size larger than that which can be obtained by the usual upsetting process is desired the bolt or screw must be machined out of larger stock than is desired for the shank, or the head must be welded to the shank.

The object of the present invention is to provide a process for upsetting or heading blanks for cap-screws, set-screws or the like by which a much greater length of material can be upset to form the head than is possible with the processes heretofore employed.

My improved process comprises the expanding into the die first of a portion of the blank intermediate its ends and then one of the ends.

Considering the process more specifically I surround or inclose the blank in such a manner as to permit the expanding or enlarging of a portion thereof intermediate its ends and then expand or enlarge said portion by a blow on one end of the blank and thereby partially form the head and then uncover the end on which the head is to be formed and by a second, blow thereon complete the upsetting process.

For better understanding of my invention reference is had to the accompanying

drawings showing one form of apparatus by which my improved process may be carried out, in which—

Figure 1 is a side elevation of an upsetting machine with parts thereof in section. 60 Fig. 2 is an enlarged detail in section showing the dies in position for performing the first step of the upsetting or heading process. Fig. 3 is a similar view showing the parts in position when the first step in the upsetting process has been performed and showing the blank or stock partially upset. Fig. 4 is a sectional view similar to Figs. 2 and 3 showing the parts in position when the process of upsetting is completed and showing the blank or stock with the upsetting completed. Fig. 5 is a view of the blank as fed into the machine. Fig. 6 is a view of the same after the first blow has been struck showing the blank enlarged at a point intermediate its ends. Fig. 7 shows the same after the upsetting is completed. Fig. 8 shows the same with the head trimmed and the shank threaded to form a set screw.

Referring now to the figures of the drawings 10 represents a part of the frame of the machine provided at the top with a guideway 11. Suitably mounted at one end of the frame is a main operating shaft 12, which is provided with a crank 13 to which is attached one end of a connecting rod or pitman 14. Mounted to slide in the guideway 11 and adapted to be reciprocated by the connecting rod is a cross head or slide 15 to which the opposite end of the rod 14 is connected at 16. At the end of the slide 15 is a die or punch holding block 17 which is adapted to be reciprocated by the slide 15, and also to move vertically with respect thereto as will be explained. The block 17 has an enlarged lower face 17^a which is adapted to be engaged by mechanism to be explained to shift the block vertically. Secured to the top of the block 16 is a guiding and holding member 18 provided with a portion 18^a which extends over the slide or cross head 15 and a portion 18^b at right angles to the portion 18^a and extending downward into an open slot 18^c in the top of the slide or cross head. The engaging faces of the members 15, 17 and 18 are carefully machined, so that although the block 17 is held against the end of the slide or cross head 15 by the portion 18^b of the member 18, it may slide upward and downward across the end 110

of the cross head. Secured to the block 17 are head forming members or punches designated 19 and 20 respectively, the member 20 being directly below the member 19. The 5 member 19 as will be explained more fully partially accomplishes the upsetting at one stroke of the cross head and then the block 17 is raised presenting the punch 20 to the blank and at the second stroke this punch 10 completes the upsetting process.

At the end of the frame is a die 21 which is provided with a passageway 21^a adapted to receive the blank and at its outer face with a cavity 21^b in which the head of the 15 bolt or rivet is formed, the shape of the cavity being in this case such as to form a so called square head. The passageway 21^a is enlarged at 21^c for a purpose which will hereinafter appear. The passageway 21^a 20 and cavity 21^b are directly in line with the head forming member 19 when the block 17 is in its lowermost position. The end of the frame against which the die rests is provided with a passageway 22 in line with the 25 passageway 21^a and entering the passageway in the die is a pin 23 which forms a backing for the blank when the head is formed and kicks the blank out of the die when the upsetting is completed. The mechanism for 30 accomplishing the latter will be explained later.

The upsetting member 19 is provided with a sleeve or tubular member 24 which is fixed at one end in the block 17 and is provided on the exterior near the outer end with a reduced portion 24^a forming a shoulder 24^b. The interior of the tubular member 24 is of two diameters the inner end being larger than the outer forming on the 40 interior a shoulder 24^c. Slidably mounted on the interior of the sleeve 24 and fitting closely therein is a plunger 25 provided with a bore 26 which is adapted to receive the end of the blank during the first step 45 of the upsetting process so that the plunger 25 surrounds the end of the blank. The plunger 25 has at its inner end a nut or ring 25^a which is adapted to engage the inner shoulder 24^c so as to limit the outer movement of the plunger, and at its opposite end an outer enlarged portion forming a shoulder 25^b and with a further enlarged portion forming a second shoulder 25^c. The 50 plunger is normally held in its outer position by means of a coil spring 27 which surrounds the outer end of the holding sleeve and the adjacent portion of the plunger and bears against the shoulder 24^b and the shoulder 25^c. In the bore 26 of the plunger 24 is arranged a punch 28 which is preferably so arranged as to slide freely therein, but its outward movement is limited by a head 28^a on its inner end adapted to engage the inner end of the plunger. The punch 60 28 is shorter than the plunger 25 so that

when the spring 27 is compressed and the plunger 25 is in its innermost position the end of the plunger will engage the block 17 at the same time the shoulder 25^b engages the outer end of the holding sleeve 24. The 70 punch or upsetting member 20 is simply a hardened steel block having a flat outer face and rigidly mounted on the block 17.

The mechanism for raising the block or punch holding member 17 after the first 75 stroke or after the upsetting is partially completed by the member 19, and the mechanism for kicking the headed bolt or rivet out of the die after the heading or upsetting is completed will now be described. Mounted upon the main shaft 12 is a gear wheel 29 which meshes with a second gear wheel 29' mounted upon a shaft 30 which is below the main shaft 12. Mounted upon a shaft 31 near the opposite end of the machine and below the block 17 is a cam 32 which is adapted to engage the lower face of the block 17 so as to raise the latter at the proper time to present the punch 20 to the blank. The cam 32 is connected in this 80 case to the gear wheel 29' by means of a connecting rod 33, so that the cam and the gear wheel will rotate in unison. The gear wheel 29' is preferably twice the size of the gear wheel 29 so that the former will make one revolution while the gear wheel 29 and the shaft 12 will make two revolutions, and the cam 32 is so constructed that, after the heading or upsetting is partially completed by the member 19 and during the second 85 stroke of the slide or cross head, it will raise the block 17 and will hold it in its upper position, while the punch 20 strikes the blank and completes the heading.

In order that the blank may be kicked out 90 of the die when the heading or upsetting is completed I connect the pin 23 which extends into the passageway or bore of the die from the rear, to one end of a lever 34 which is pivoted intermediate its ends on 95 the frame of the machine at 35 and is connected at its opposite end to a plunger 36 which is slidably mounted in the frame of the machine and carries at its inner end a roller 37 which engages a cam 40 (shown by 100 dotted lines in Fig. 1) mounted on the shaft 31. The lower end of the lever 34 and the plunger 36 are held in their innermost positions by means of a spring 39, the inward movement being limited by a flange 36^a on 105 the plunger 36. When the parts are in this position the pin 23 is held in its outermost position or in the position to form a backing for the blank. The cam 40 is so formed 110 that after the second forward stroke of the slide or cross head 15 and after the punch 20 has completed the upsetting it will come in contact with the roller 37 and force the plunger 36 outward shoving the lower end 115 of the lever 34 outward and moving in the 120 125 130

upper end which shoves in the pin 23 which comes in contact with and kicks out the finished product.

The operation of the machine and the 5 steps of the process will now be described more fully. Although in a machine employed for carrying out my process the blanks will be cut from a long piece of stock material and will be fed to the die automatically, I have not shown this part, but with the simple apparatus here shown the blanks will be fed by hand. When the blank which is shown in Fig. 5 is placed in the die and before the beginning of the stroke which 10 forms the first part of the upsetting, the parts are in the position shown in Fig. 1, the heading member 19 being in line with the blank. As the slide 15 moves forward and the plunger 25 approaches the die, the end 15 of the blank which projects beyond the die enters the passageway in the end of the plunger 25, the passageway being just large enough to permit the end of the blank to pass freely therein. As the slide and the 20 parts carried thereby continue toward the die, the end of the plunger engages the face of the die and the end of the pin 23 engages the outer end of the blank, the parts then being in the position shown in Fig. 2. 25 Further movement of the parts causes the plunger to slide inward relative to the sleeve against the tension of the spring, and as the inner end of the punch is in engagement with the block 17, the metal of the blank is 30 compressed, but as the outer end of the blank is surrounded by the end of the plunger this part cannot be upset, and as the metal will expand along the lines of least resistance, the force of the blow causes the metal inter- 35 mediate the ends of the blank to expand outward and partially fill the cavity in the die. The position of the parts at this stage of the upsetting process is shown in Fig. 3, and the shape of the head so far formed 40 is shown in Fig. 6. The heading member 20 is then drawn away from the die 21 by the return stroke of the slide or cross head. During the second stroke of the latter the block 17 is shifted by the cam 45 32 and at the completion of the second stroke the punch 20 strikes the end of the blank

and completes the upsetting, completely filling the head cavity 21^b and the enlargement 21^c of the passageway 21^a. At the completion of the second stroke the parts are in 55 the position shown in Fig. 4. During the return movement of the cross head or slide after the second stroke the blank is kicked out of the die by the inward movement of the pin 23 caused by the cam 40 engaging 60 the roller on the end of the plunger 36 and shifting the lever 34. When the headed blank is knocked out of the die it will be as shown in Fig. 7. The body of the shank will have the same diameter as the blank had 65 when it was fed into the machine but there will be an enlarged portion 38^a next to the head. A thread is then rolled on the body of the blank and as the rolling of a thread always increases the diameter of the shank 70 the threaded portion will then have the same diameter as the enlarged part 38^a. The shank therefore will have a uniform diameter from end to head instead of having, as in the usual form, a section of smaller 75 diameter between the threaded part and the head.

What I claim is,—

The process of upsetting or heading blanks for cap-screws, set-screws, and the 80 like, which consists in providing a die having a matrix of the size and shape of the complete head which is to be formed, then introducing the blank into the die so that the inner end of the blank projects beyond 85 the matrix, inclosing the projecting end of the blank and applying pressure thereto to crowd a portion of the projecting end back into the matrix while maintaining the remainder of the projecting portion the same 90 shape and cross section as the blank, then removing the inclosing means from the projecting end and upsetting the said projecting end into the matrix.

In testimony whereof, I sign the foregoing specification, in the presence of two witnesses.

THOMAS FERRY.
